UNITED STATES PATENT OFFICE.

SAMUEL E. DOANE, OF CLEVELAND, OHIO.

ELECTRIC SIGN.

No. 882,555.

Specification of Letters Patent. Patented March 24, 1908.

Application filed April 25, 1907. Serial No. 370,137.

To all whom it may concern:

Be it known that I, SAMUEL E. DOANE, a citizen of the United States, residing at Cleveland, in the county of Cuyahoga and State of Ohio, have invented a certain new and useful Improvement in Electric Signs, of which the following is a full, clear, and exact description.

The object of the present invention is to provide an illuminated sign having an effectiveness superior to that of any now known and capable of effects not now had with present forms.

My invention is directed particularly to electric signs in which the use of incandescent lamps is relied upon for the results obtained.

Various distinct features, characteristic of my construction, will be pointed out in the following specification, reference being had to the accompanying drawings in which

Figure 1 is a front elevation of a sign embodying the characteristic features of my invention and in which Fig. 2 is a perspective view looking at the same somewhat from the side.

In a great majority of the illuminated signs heretofore used, the source of illumination has been confined behind the frame work having translucent openings disposed in the form of the desired characters, being contrasted with relatively opaque or different colored translucent background. Such signs, while possibly effective enough to an extent, if viewed from the front, are so exceedingly ineffective and disappointing when viewed from any position except the front that they have practically ceased to be of use, and at present advertisers rely more particularly upon incandescent lamps placed upon an opaque background, the lamps being in the outline or form necessary to present the advertisement desired. This is the most effective illuminated sign now in use. Such signs are, however, of practically no value or effect whatever during the day as the characteristic outline of the letters is very difficult to distinguish, being confused with the frame work of the supporting field.

I have discovered that, by making up the entire field of the sign of incandescent lamps and preferably having the letters or characters, A, made of colored glass bulbs while the background, B, of the field is composed of clear translucent bulbs, the effect at night, under illumination, is brilliant and startling

and different from that obtained by any other form of illuminated signs, and this, in marked distinction from and contrast with those signs in which a light is placed behind a perforated frame work, is quite as effective 60 viewed obliquely as when viewed from the front.

The old type of perforated sign, with or without different colors of glass in the perforations is without value when viewed 65 obliquely, especially owing to the essentially exclusively forward flow of light, which occurs in such signs, where the source of illumination is necessarily somewhat behind the plane of the transparent openings. This distinction should be well borne in mind as it is 70 of the most important character when the effect of the sign at night is considered.

In the day time my sign is as effective as any painted sign, since the contrast between 75 the glittering field of transparent bulbs in the background and the colored bulbs forming the letters or characters is such as to at once attract attention. Furthermore, in my sign, as distinguished from those illuminated signs 80 in which the light is placed back of the frame and the contrast obtained by different colors of glass over the perforations, the effect of the contrasting colors in the daylight is very marked, since the light coming from the 85 bulbs is, in the case of the clear transparent bulbs, transmitted light, and by consequence, the contrast between the clear bulbs and the colored bulbs is fully as great as at night; whereas, in the old form of illuminated sign only reflected light comes in the 90 day time from the transparent glass which covers the perforations in the casing containing the illuminating lamps, and for this reason, it frequently happens that the clear 95 glass is indistinguishable from the colored glass. Furthermore, it is possible, with the arrangement that I have adopted, to obtain an additional effect at night by flashing the 100 bulbs which compose the characters constituting the sign. By flashing these bulbs and allowing the background to remain illuminated, the full effect of flashing may be obtained, whereas in the case of those 105 illuminated signs where there is no background, the flashing of the sign presents merely the effect of total darkness between flashes, during which time the eye is not attracted to the sign in any manner.

For the above and other reasons, the con- 110

struction which I have produced is effective to the greatest degree both as a night and day sign.

Having thus described my invention, I 5 claim:

An illuminated sign in which the characters and the field forming the background therefor are composed of incandescent lamp

bulbs, the bulbs of the characters and those of the field being contrasted in color.

In testimony whereof, I hereunto affix my signature in the presence of two witnesses.

SAMUEL E. DOANE.
